Primary Examiner—Stella Reid*Assistant Examiner*—Celia A. Murphy*Attorney, Agent, or Firm*—Richard C. Litman[57] **CLAIM**

The ornamental design for a winged applique for a shirt, as shown and described.

DESCRIPTION

FIG. 1 is a front perspective view of a winged applique for a shirt showing my new design;

FIG. 2 is a front elevational view thereof;

FIG. 3 is a top plan view thereof;

FIG. 4 is a bottom plan view thereof;

FIG. 5 is a left side elevational view thereof, the right side elevational view being a mirror image thereof; and, FIG. 6 is a rear elevational view thereof.

The broken lines partially showing a human form in FIGS. 1, 2, and 6 are for illustrative purposes only and forming no part of the claimed design; and the broken lines shown on the claimed article throughout the views being understood to represent conventional stitching.

FIG. 3

FIG. 4

FIG. 5
